UNITED STATES PATENT OFFICE

HANS KREIDEL, OF WIESBADEN, GERMANY

WICK LUBRICATOR

Application filed November 12, 1928, Serial No. 318,685, and in Germany May 3, 1928.

The present invention relates to a wick oiler provided with a container for the supply of lubricant capable of withstanding pressure and having an automatic air release 5 and air inlet device and a non-return-valve, and of which the suction wick provided in the outflow pipe is secured against accidental movement. The new wick lubricator is adapted to effect continuous lubrication for 10 a long period of time, and if desired enables lubrication to be effected at any time by means of a high pressure pump. The latter is necessary for commencing the wick lubrication when the wick does not produce an 15 effective suction action and is also necessary to remove any stoppages which may be caused in the passages or bores through which the lubricating oil is to pass.

In the accompanying drawing is illustrated 20 by way of example in longitudinal section a wick lubricator for wick lubrication and direct high pressure lubrication. The wick lubricator is not secured directly to the point to be lubricated by means of a screw nipple 25 secured thereto, but by means of a separate hollow screw which passes through the bore of a separate securing member, is tightly guided in this and is provided with a separate nipple extension containing a non-return-valve. In the drawing *a* indicates a 30 pressure tight container for the supply of lubricant in the bottom *a*¹ of which is secured a pipe *b* open at the bottom and extending to near the top of the container. The 35 passage *c* in this pipe communicates at the top with a radial passage *c*¹ leading into the interior of the container. On the upper portion of this air inlet and outlet pipe *b* slides a cork washer *d* provided with a metal bushing, this float rising and sinking with the 40 level of the lubricating oil and thus exposing or closing the passage *c*¹. An extension *a*² of the bottom *a*¹ of the supply container *a* serves for securing the latter to the point to 45 be lubricated. The extension *a*² has a transverse passage and through this passage is passed in a fluid-tight manner the hollow screw *e* provided with an annular groove *e*¹. The screw *e* is screwed into the screw threaded hole of the member to be lubricated. The 50 collar *f* of the screw *e* presses the extension *a*² of the supply container tightly against the member to be lubricated when the screw *e* is tightened. The outlet passage *a*³ of the container *a* registers with the annular groove *e*¹ of the hollow screw when the apparatus is in position and the annular groove is connected by a radial passage *e*² with a longitudinal passage *e*³ in the screw *e*. This longitudinal passage *e*³ is reduced in diameter at its rearward portion and the reduced portion is adapted to receive a suction wick *h* held in position by an annular member *g*. In the front enlarged portion of the passage *e*³ is fitted a connecting nipple *k* provided with a non-return-valve *i*, this nipple being adapted to be connected to a suitable lubricating pump.

The method of operation of the wick lubricator above described is as follows:

Lubricating oil is pumped by a suitable pump into the wick lubricator through the nipple *k*. As the direct passage to the point to be lubricated is through the suction wick *h* the lubricant passes along the path of least resistance, therefore, through the passage *e*², the annular groove *e*¹ and the outlet passage *a*³ into the supply container *a*. The air contained in the latter escapes to the outside through the passages *c*¹ and *c* and as soon as the lubricating oil which is pumped in has reached a predetermined level the rising lubricating oil raises the float *d*, slidably mounted on the pipe *b* and closes the passage *c*¹. By pumping in additional lubricating oil any air contained under the top of the container is compressed and by reason of the greater resistance now present in the container the lubricant is forced through the suction wick *h* directly to the point to be lubricated. This is thus thoroughly lubricated as is the case when lubricating under high pressure and any dirt which may have entered the point to be lubricated is thus removed. The pressure existing in the supply container assists the suction action of the wick, after the operation of the pump has ceased, until an equalization of pressure occurs. Equalization of pressure occurs as soon as the float, by reason of the action

of lubricating oil, has sunk to such an extent that the passage e^1 is again exposed. From now on only atmospheric pressure acts on the lubricant and the wick lubricator now operates in the usual manner.

It is essential that the passage e^2 leading from the passage e^3 to the outlet passage a^3 of the container is located between the suction wick h , disposed in the reduced portion 10 of the passage e^3 , and the non-return valve i as with such an arrangement it is possible to force the lubricating oil by means of the high pressure pump to the point at which the resistance is lowest, therefore either into 15 the container or through the suction wick directly into the member to be lubricated.

I claim as my invention:

1. In a lubricator, a reservoir, an automatic air valve therefor comprising a tubular member providing a passageway connecting said reservoir with atmosphere, and a float 20 for closing said passageway, an inlet nipple provided with a non-return valve, a passageway connecting said reservoir with a part 25 requiring lubrication, and a wick in said passageway.

2. In a lubricator, a reservoir, an inlet nipple therefor provided with a non-return valve, a passageway connecting said reservoir with a bearing to be lubricated, an air 30 vent for said reservoir comprising a tubular member vertically positioned within said reservoir, a transverse passageway in said tubular member, and a float member slidably 35 mounted on said tubular member and adapted to close said passageway when said reservoir is filled to a predetermined height.

3. A wick lubricator comprising a lubricant reservoir, a base member attached thereto and having screw-threaded engagement with a bearing to be lubricated, an annular groove in said base member adjacent an opening to said reservoir, a passageway longitudinally disposed in said base member 40 having a lubricant fitting entering one end, and a wick member extending from a point adjacent the middle thereof to the other end, a check valve in said lubricant fitting, and a valve for closing a passageway from said 45 reservoir to atmosphere after a predetermined quantity of lubricant has been placed in said reservoir.

In testimony whereof I affix my signature.
HANS KREIDEL.
